CHAIR TIP

Charles W. Moore, Fullerton, Calif.

Application July 12, 1937, Serial No. 153,173

4 Claims. (Cl. 16—42)

My invention relates to tips for the lower extremities of furniture legs, and particularly to chair leg tips. Among its principal objects are; first, to provide an improved article of this nature which will afford, under all ordinary conditions of service, great resiliency of support; second, to supply a chair leg tip which permits the leg to be tilted through an unusually great angle, without interfering with the seating of the device upon the floor; third, to greatly impede transmission of sound vibrations through such a tip, so that there will be a minimum of noise when thus-equipped furniture is caused to slide over marble or cement floors; and, fourth, to accomplish the stated purposes in a simple and relatively inexpensive construction, which may be readily applied without special tools.

It is well known to those familiar with this art, that the resilient cushioning member should be relatively thick, and be afforded the greatest possible bearing surface. Otherwise it is difficult to secure either sufficient "yield", or satisfactory "life". Moreover, the resilient member should be thickest adjacent its periphery, because the greatest force of compression is likely to be exerted there. This is particularly true when chair legs are not vertical, or when they may be frequently tipped by their users.

It is also well known that provision should be made for permitting the entire bottom surface of the device to remain in contact with the floor, even though the cooperating chair leg is non-vertical by a substantial angle. Unless the tip is adapted to fully seat its bottom surface upon the floor, pressure will be localized and intensified at the contact area. The result is almost certain damage to soft floors, such as those covered with linoleum for example; and, since it localizes wear on the tip, the useful life of the device tends to be proportionally reduced.

Still further as to objects, it is highly desirable for devices of this class to possess sound absorbing qualities in a marked degree. In large rooms filled with people, the noise due to moving chairs, particularly when they are slid over marble or cement floors, may be very objectionable.

In my improved construction, means have been adopted for attaining all of the objects which have been indicated as being desirable. Moreover, I have made it feasible to make use of very hard (and expensive) metal where wear occurs, and of soft (and cheap) material elsewhere. This greatly reduces manufacturing cost when comparison is based upon quality and capacity for wear.

My objects are attained in the manner illustrated in the accompanying drawing, in which:

Figure 1 is an elevation of an approved embodiment of my device in axial section, and indicates its functional relationship to a co-operating chair leg;

Figure 2 is a plan view of the tip construction shown in Fig. 1, after the resilient cushioning member has been removed; this view being partly in section taken on the plane 2—2 of Fig. 1;

Figure 3 illustrates another approved embodiment of my invention in axial section; and is similar to Fig. 1;

Figure 4 is a plan view of the tip construction shown in Fig. 3, after the resilient cushioning member has been removed; this view being partly in section taken on the plane 4—4 of Fig. 3;

Figure 5 represents a slightly modified form of the construction shown in Figs. 1 and 2, this form being adapted for use when the utmost possible elimination of noise is not imperative; and

Figure 6 is a fragmentary elevation of the lower end of a steel chair leg, indicating the manner in which tips of the general form shown in Figs. 3 and 4 may be attached thereto.

Similar reference numerals refer to similar parts, throughout the several views.

My invention, in any of the forms it may preferably assume, comprises a circular base-cup 11, which may be made of hardened steel. This has a flat sole or bottom surface at 12, and a rounded periphery at 13. This form of base has been found to be much the easiest on floors, especially relatively soft floors such as those covered with linoleum, since it provides the maximum bearing surface. The sole or bottom surface is polished to reduce friction.

Within the base cup, and attached thereto, is a domed washer-like member, as at 14 and 14' of Figs. 1 and 3 respectively. These members take the general form of an inverted saucer; and, in co-operation with the base cup, afford a chamber 15 for loosely containing and confining the heads of whatever attachment means are to be employed, such as the part 16 of Fig. 1 or 16' of Fig. 3.

In Figs. 1, 2, and 5, an ordinary nail 17 is employed for attaching my device to the lower extremity of a wooden chair leg 18. In Figs. 3 and 4, a square headed lag screw 19 is shown similarly employed. Fig. 6 shows a common form of lower extremity of a steel furniture leg at 21, and here the attaching means comprises a bolt 22 and a nut 23.

In each case, the shank of the attaching means

55

passes through a hole 24 in the center of the domed members 14 or 14'. The diameter of this hole is much larger than that of the shank, to permit the latter and the chair leg to assume very substantial angularity with respect to the axis of the domed member. Such angularity with respect to the chair leg is shown by dotted lines 25.

The under surface of the central portion of domed members 14 and 14' is made spherical, as shown at 26 and 26'. The head of the attaching means is either made circular, as indicated at 16, or a circular washer 27 is employed above the head. The entire peripheries of these circular heads or washers are adapted to seat upon spherical surfaces 26 or 26' independently of the angular position.

Members 14 and 14', in my improved construction, usually are made of soft steel, and are attached to the base cup by means of spot-welding. This may be accomplished very satisfactorily by forming these members with three equally spaced projections 28, on their under surfaces near the peripheries; corresponding depressions, above these projections, being shown on the drawing at 29. One electrode of an electric welder may be made to engage the upper surfaces of members 14 or 14', and the other electrode be connected to base cup 11. The welding current will then have to pass through the contacts at projections 28, and the welding will be greatly facilitated by reason of the small area of these contacts and their relatively large contact resistances.

The cushioning member of my device comprises a circular rubber washer 31. This has a flat surface at the top, to seat against the lower extremity of the chair leg to which the device is attached. The lower surface of the rubber washer is shaped to seat upon the entire upper surface of member 14 and 14' as the case may be, as well as upon rim 11 of the base member. Thus the duty imposed upon the rubber is spread over the largest possible area, and the life of the rubber is prolonged in consequence.

When the device is to be screwed upon the extremity of a chair leg, as illustrated in Fig. 3; or is to be bolted thereto, as indicated in Fig. 6; the attaching means may have a square head which fits loosely within a square recess 32 in member 14'. In such case the fit should be close enough to prevent the head from turning in the recess, but loose enough to permit the necessary angularity of positioning that has been described above.

I prefer to make washers 27 of such material as indurated wood or asbestos fibre, because of the very great sound-deadening qualities possessed thereby. When this is done, although the device will be firmly held in place at all times, there will be no metallic connection whatever between the base cup and the chair leg. Sound vibrations, originating in the base cup, will be almost completely absorbed for this reason, and there will be a minimum of noise in using furniture thus equipped.

Having thus fully described my invention, I claim:

1. A device of the character described, comprising; a copper base; a co-axial washer with a square dome, within the base and affixed thereto; an attaching member, having a square head loosely confined within the dome and prevented from substantial axial turning thereby, and a shank extending through a substantially larger central hole in the domed washer; and a co-axial cushioning pad seated upon the entire outer surface of the domed washer; the central portion of the inner upper surface of the domed washer being spherical; and said head being adapted to engage said inner surface throughout the entire length of an annular area at the periphery of an interposed flat washer which is co-axial with the head.

2. A device of the character described, comprising; a base; a domed washer affixed to the base; an attaching member, having a head loosely confined within, and a shank extending through a substantially larger central hole in, the domed washer; a co-axial cushioning pad seated upon the entire outer surface of the domed washer; and a co-axial circular flat washer upon said shank just above said head; the central portion of the inner surface of the domed washer being spherical; and said circular washer being adapted to engage said inner surface throughout the entire length of the periphery of the circular washer.

3. A construction as defined in claim 2, wherein the circular washer is of material adapted to greatly impede the transmission of sound vibrations therethrough.

4. A construction as defined in claim 2, wherein the circular washer is of relatively incompressible material, and also adapted to greatly impede the transmission of sound vibrations therethrough.

CHARLES W. MOORE.
